UNITED STATES PATENT OFFICE.

WILFRED B. GODDARD, OF SAN FRANCISCO, CALIFORNIA, ASSIGNOR TO THOMAS DAY COMPANY, OF SAN FRANCISCO, CALIFORNIA, A CORPORATION OF CALIFORNIA.

DESIGN FOR A WALL BRACKET.

Application filed February 16, 1925. Serial No. 12,387. Term of patent 7 years.

To all whom it may concern:

Be it known that I, WILFRED B. GODDARD, a citizen of the United States, and a resident of the city and county of San Francisco, State of California, have invented a new, original, and ornamental Design for a Wall Bracket, of which the following is a specification, reference being had to the accompanying drawings, forming part thereof.

In said drawings—

The figure is a perspective view of a bracket, showing my new design, a lantern supported by the bracket being shown in light lines.

I claim:

The ornamental design for a wall bracket substantially as shown.

WILFRED B. GODDARD.
